THREAD-PARTING MECHANISM FOR LOOMS

Application filed February 2, 1929. Serial No. 337,014.

This invention relates to filling replenishing looms and is more particularly directed to means for parting the spent filling at a point between the shuttle ends and preferably adjacent the shuttle eye on call for replenishment of filling.

It is well known to those skilled in the art that when replenishment of filling is to be effected, the old filling extends from the cloth selavage through the shuttle eye to the bobbin about to be ejected, and various mechanisms have been devised to part this old filling in such manner that it may not be carried into the shed or become tangled with the incoming filling.

Among these prior efforts some mechanisms have been devised to part the spent filling adjacent the shuttle eye, and in some cases the parting mechanism has been supplied with clamping instrumentalities for withdrawing the end of the filling leading to the cloth selvage in a frontward direction out of the shuttle box, so that when the substantially denuded filling carrier or bobbin is ejected from the shuttle during replenishment, all liability of carrying the spent filling end into the shed has been avoided.

In such prior mechanisms, however, the parting means has usually been actuated to part the filling adjacent the shuttle eye, either by movement of the transerrer during replenishment or by frontward movement of the lay, and in instance of the former mechanism is found in the patent to Alfred E. Stafford, No. 1,552,388, dated September 1, 1925.

When the spent filling is parted adjacent the shuttle eye through the medium of the transerrer movement, the incoming filling carrier or bobbin is liable to displace the outgoing filling carrier or bobbin before the spent filling is parted, and in some cases breakage of the spent filling is liable to occur.

One of the objects of the present invention is to insure parting of the spent filling prior to the completion of the replenishing operation and preferably as the incoming filling carrier or bobbin leaves the hopper under the control of the transerrer.

In some cases where the filling is parted

through the action or movement of the transerrer, the mechanism has precluded the use of a transerrer having a bobbin tip engaging portion and also has precluded the use of a bobbin tip guide for directing the tip of the bobbin into the shuttle. 55

In accordance with the present invention, the parting means for the spent filling is made effective to part the filling adjacent the shuttle eye through the movement of a bobbin guide which is displaced or moved by the incoming filling carrier as it leaves the hopper, thereby doing away with the complicated and congested condition of the mechanism and permitting the use of a transerrer having a bobbin tip engaging portion and a bobbin tip guide for directing the tip of the bobbin into the shuttle. 60 65

The invention and new features thereof and novel combination of parts will best be 70 made clear from the following description and the accompanying drawings of one good practical form of the invention.

In the drawings:

Fig. 1 is a perspective view of a filling replenishing loom at the replenishing side thereof, some of the parts of the loom structure being omitted; 75

Fig. 2 is an end elevation, with parts in section, showing the position of parts when 80 the bobbin guide is moved by an incoming filling carrier as it leaves the hopper; and

Fig. 3 is a perspective view in detail of one good practical form of parting means. 85

The loom frame 1 may be of usual construction and as shown is provided with a hopper stand for the support of the well-known rotary hopper in which bobbins or filling carriers are mounted for transfer to the shuttle from time to time. As shown, 90 the loom is provided with a hopper stand having a foot 2 which may be appropriately secured to the loom frame by bolts 3, and rising from the foot 2 is the hopper supporting plate 4 through which extends the stud 5 carrying the rotary hopper 6 in which the bobbins or filling carriers 7 are mounted. 95

The rotary hopper 6 is provided with suitable means for periodically rotating the hopper to bring successive filling carriers or bob- 100

bins into transferring position, and, in the present instance, the rotary hopper is provided with a ratchet or toothed member 8 by which, through a suitable train of mechanism not necessary here to describe because it is well-known, the hopper may be rotated step-by-step to position successive filling carriers or bobbins for transfer. When a filling carrier is in transferring position and still in the hopper it rests against the fixed abutment 9, and opposed to such abutment 9 is a bobbin guide which normally underlies in part a filling carrier when it is in transferring position. In the present instance of the invention, the bobbin guide 10 is carried by an arm 11 pivotally mounted on the hopper stand at 12 and capable of swinging or yielding movement. The bobbin guide 10 has a bevelled or inclined portion 13, so that upon movement of a filling carrier or bobbin from the hopper the bobbin guide 10 will be displaced or moved, in the present instance, rearwardly.

Connected to the arm 11 is a light spring 14 normally tending to hold the arm 11 and the bobbin guide 10 in position with the inclined portion 13 of the bobbin guide extending beneath the filling carrier or bobbin then in transferring position. In order to limit the swinging movement of the arm 11 an adjustable stop 15 may be employed, all as more fully described in detail in the patent to Edward C. Burnham and Harry A. Davis, No. 1,626,505, dated April 26, 1927.

Mounted upon the hopper stand is the transferrer shaft 16 having the transferrer 17 mounted thereon and normally held in raised position by a spring 18. The transferrer 17 has a bobbin head engaging portion 19 laterally from which extends the arm 20 carrying a bobbin tip engaging portion 21, the construction being such that upon actuation of the transferrer the bobbin in position for transfer in the hopper will be engaged at its head and tip portions for transfer to the shuttle during replenishment.

Secured to the transferrer shaft 16 is the backwardly extending arm 22 having pivoted thereto at 23 the bobbin tip guide 24 for guiding the tip of the bobbin into the shuttle during transfer.

In accordance with the present invention the spent filling is to be parted between the ends of the shuttle or preferably adjacent the shuttle eye, and as shown the front wall 25 of the shuttle box is provided with an opening 26 into which the parter may extend to engage and part the spent filling on call for replenishment.

In the present instance of the invention the front wall of the shuttle box is provided with an inclined opening 27 similar in this respect to the patent to Alfred E. Stafford previously mentioned, whereby if desired the parting means when provided with a clamp

may withdraw the filling frontwardly from the shuttle box after it has been parted and over the top thereof. This construction constitutes a good practical form of the invention in these respects but obviously the invention as will more fully appear is not restricted thereto but may be associated with any character of parting means to part the filling adjacent the shuttle eye and withdraw the filling frontwardly around the cloth selvage as a center.

Secured to the laterally projecting end of the transferrer shaft 16 is a depending bracket 28 having suitable guideways 29 in which is mounted for sliding movement the carrier 30. As hereinbefore indicated, the parting means may be of any usual or desired character but as shown in the present instance of the invention it comprises cutting members 31 and 32 pivotally mounted at 33 upon the slide 30. In most cases it will be desirable to provide the parting means with a thread clamp, and to this end the cutter member 32 of the parter is faced with friction material 34, as indicated in Fig. 3, which in cooperation with the companion clamp 35 serves to clamp that portion of the thread leading to the cloth selvage when the spent filling has been parted.

In order that the thread parter and clamp as shown may occupy an operative position in the opening 26 of the shuttle box when it is moved rearwardly, as will be hereinafter described, the slide 30 is provided with an adjustable stop 36 which by contact with the lay limits the rearward movement of the parting means.

Mounted for rocking movement on the transferrer shaft 16 is the yoke member 37 having a downwardly extending arm 38 provided with a slot 39 which engages a pin 40 extending from the slide 30, the construction being such that should the yoke member 37 be turned upon the transferrer shaft 16 in a clockwise direction, in the present instance, the slide 30 will be moved rearwardly into operative position.

The yoke member 37 is preferably formed of two parts adjustably connected together by a bolt 41, as more clearly shown in Fig. 1, and the outer end of the yoke member 37 is mounted for rocking movement on the transferrer shaft 16, as indicated at 42, while its inner end is mounted for rocking movement on an extension of the transferrer shaft 16, as indicated at 43. The yoke member 37 has an upstanding lug 44 to which is pivotally connected at 45 the yielding arm or link 46, the outer end of which at 47 is preferably joined to an arm 48 secured to the transverse or rock shaft 49 which may be of usual construction. The transverse or rock shaft 49 is mounted upon the front of the loom in suitable bearings 50 and is connected as usual to a train of mechanism controlled by a feeler

or other detecting means so that it may be rocked forwardly in the direction of the arrow, Fig. 1, when the feeler or detecting means calls for replenishment of filling, the result being that in such event the parting means will be moved rearwardly into operative position to part the filling adjacent the shuttle eye.

Mounted for rocking movement on the 10 transerrer shaft 16 is the yoke member 51 which is mounted for rocking movement at its outer end upon the transerrer shaft at 52 and at its inner end is mounted for rocking movement on the extension 43, as hereinbefore described. The yoke member 51, like the yoke member 37, may be formed of two parts adjustable relative to each other by means of a bolt 53.

Rising from the yoke member 51 at its 20 inner portion is an arm 54 preferably connected at 55 with a yieldable link 56 which may be of the general type as that shown and described in the Stafford patent, hereinbefore mentioned. The opposite end of the yielding 25 link 56 is connected at 57 to the swinging arm 11 which carries the bobbin guide 10. In the present instance, the swinging arm 11 carries an adjustable pin 58, the end of which may be connected to the yieldable link 56 30 to thereby move the link in the direction of the arrow, Fig. 1, when the filling carrier or bobbin in the hopper is being moved from the hopper during replenishment of filling.

The outer end portion of the yoke member 51 carries a parter actuator 59 which may be suitably supported in a head 60. The parter actuator 59 has its lower end portion turned rearwardly, in the present instance, as indicated at 61, and is adapted on downward 40 movement of the parter actuator to engage a pin 62 extending laterally from the movable parting member 32, the construction being such that when the bobbin guide 10 is moved rearwardly, as indicated in Fig. 2, during 45 the passage of the filling carrier or bobbin from the hopper towards the shuttle, the yoke member 51 will be rocked, to thereby depress the parter actuator 59 and cause the parter to part the thread adjacent the shuttle eye, with the result that the thread is parted during the passage of the incoming filling carrier or bobbin from the hopper towards the shuttle and prior to the time that such 50 filling carrier or bobbin has been completely transferred.

From the construction described as one good practical form of the present invention it will be apparent that upon call for replenishment of filling by rocking movement of 55 the transverse or rock shaft 49, the slide 30 with the parter connected thereto will be moved rearwardly to operative position, and when the filling carrier or bobbin next to be transferred is being moved from the hopper 60 towards the shuttle, the bobbin guide will be

70 moved to thereby rock the yoke member 51 and cause the parter actuator to part the filling adjacent the shuttle eye before complete passage of the incoming filling carrier or bobbin into the shuttle.

75 As hereinbefore described, the parter or parter and clamp comprises the construction indicated in Fig. 3, and in order that the parter may be opened as it is being moved to rearward operative position, the bracket 28 has extending laterally therefrom the projecting portion 63 on which is pivotally mounted a trip 64 which has pivotal movement forwardly and is stopped in its pivotal movement rearwardly by the lower portion 65 of the trip, with the result that when the partner members have been closed and the thread parted by the actuator 59, as hereinbefore described, and if moved forwardly, the trip 64 will permit the parter to move 80 forwardly without opening the parter members so that the filling will be held or clamped by the parter until when filling replenishment is again called and the parter is moved rearwardly to operative position, the 85 trip 64 will open the members of the parter to prepare it for the reception of the spent filling adjacent the shuttle eye.

90 What is claimed is:

95 1. In a loom provided with mechanism to automatically replenish the filling in the shuttle, parting means for parting the spent filling adjacent the shuttle eye when the shuttle is boxed for replenishment, mechanism for moving the parting means into operative position on call for replenishment, a bobbin guide mounted for movement by the replenishing bobbin during its transfer, and mechanism for actuating the parter including a rocking yoke, a parter actuator carried by the yoke adjacent the delivery eye end of the boxed shuttle, and connections between the other end of the yoke and bobbin guide to operate the parter actuator to part the filling by movement of the bobbin guide 100 during replenishment.

105 2. In a loom provided with mechanism to automatically replenish the filling in the shuttle, parting means comprising relatively movable cutting members to part the spent filling 110 between the ends of the shuttle adjacent a side wall thereof when the shuttle is positioned for replenishment, mechanism for moving the parting means into operative position on call for replenishment, a bobbin guide mounted 115 for movement by the replenishing bobbin during its transfer to the shuttle, and devices for operating the parter including a rocking member extending from a point adjacent the bobbin guide to a point adjacent the outer end 120 of the boxed shuttle, a parter actuator carried on the outer end of the rocking member, and connection between the rocking member and bobbin guide for operating the parter adjacent the eye of the shuttle by movement 125 130

of the bobbin guide during replenishment.

3. In a filling replenishing loom, the combination of a hopper, a transerrer for transferring a bobbin from the hopper to the shuttle, parting means for parting the spent filling between the ends of the boxed shuttle adjacent a side wall thereof, mechanism for moving the parting means into operative position on call for replenishment of filling, a bobbin guide mounted for movement by a bobbin as it is transferred to the shuttle, and means actuated through movement of the bobbin guide by a bobbin during its transfer to the shuttle to cause the parting means to part the filling along a side of the shuttle, including a rocking member extending longitudinally of the hopper and carrying a parter actuator at its outer end portion, and connections between the inner end of the rocking member and the bobbin guide.

4. In a filling replenishing loom, the combination of a hopper, a transerrer for transferring a bobbin from the hopper to the shuttle, parting means for parting the spent filling between the ends of the boxed shuttle adjacent a side wall thereof, mechanism for moving the parting means into operative position on call for replenishment of filling, a bobbin guide mounted for movement by a bobbin as it is transferred to the shuttle, a rocking yoke extending longitudinally of the hopper and having a parting finger at its outer end adjacent the delivery end of the shuttle, and connections between the rocking yoke and bobbin guide for causing the finger to operate the parter by movement of the bobbin guide during transfer.

5. In a filling replenishing loom, the combination of a hopper, a transerrer for transferring a bobbin from the hopper to the shuttle, a parter for parting the spent filling at the eye end of the shuttle, a parter actuator including a rocker having a member extending in front of the hopper from its inner portion to a point opposite the eye end of the shuttle, a bobbin guide mounted for movement by a bobbin as it is transferred, and a connection between the bobbin guide and the inner end of the rocker for causing the outer end of the rocker to actuate the parter by movement of the bobbin guide during transfer of a bobbin from the hopper to the shuttle.

6. In a filling replenishing loom, the combination of a hopper, a transerrer having portions for engaging the bobbin adjacent the head and tip portions for transferring a bobbin from the hopper to the shuttle, a parter for parting the filling at the eye end of the shuttle, a bobbin guide mounted for movement by a bobbin as it is transferred from the hopper, a parter actuator mounted for rocking movement and having the portion connecting its inner and outer ends extended longitudinally of the hopper at one side of the head and tip portions of the transerrer in non-

interfering relation therewith, and connections between the bobbin guide and actuator for causing the outer end of the latter to operate the parter by movement of the bobbin guide during transfer.

7. In a filling replenishing loom, the combination of a hopper, a transerrer having portions for engaging the bobbin adjacent the head and tip portions for transferring a bobbin from the hopper to the shuttle, a bobbin tip guide for directing the bobbin tip into the shuttle, a parter for parting the spent filling along a side of the shuttle between the ends thereof, a bobbin guide mounted for movement by a bobbin as it is transferred from the hopper, a parter actuator including a yoke member mounted at its inner and outer ends for rocking movement, an arm connecting the ends of the yoke member and extending longitudinally of the hopper at one side of the transerrer and tip guide in non-interfering relation therewith, and connections between the inner end portion of the yoke member and the bobbin guide to cause the outer end of the yoke member to operate the parter and part the filling near the shuttle eye as the bobbin guide is moved during transfer.

8. In a filling replenishing loom, the combination of a hopper, a transerrer, a shaft or stud on which the transerrer is mounted, a parter for parting the spent filling adjacent the shuttle eye, a bobbin guide mounted for movement by a bobbin as it is transferred from the hopper, a parter actuator constituted as a yoke extending longitudinally in front of the hopper and mounted on the transerrer shaft or stud, and connections between the bobbin guide and parter actuator to cause the parter actuator to operate the parter to part the filling adjacent the shuttle eye as the bobbin leaves the hopper during transfer.

9. In a filling replenishing loom, the combination of a hopper, a transerrer having a bobbin head and bobbin tip engaging portions, a shaft or stud on which the transerrer is mounted, a parter for parting the spent filling adjacent the shuttle eye, a bobbin guide mounted for movement by a bobbin as it is transferred from the hopper, a parter actuator constituted as a yoke having an outer end pivotally mounted opposite the outer portion of the shuttle box and its inner end pivotally mounted opposite the inner portion of the shuttle and the connecting yoke member extending in off-set relation with parts mounted upon the transerrer shaft or stud, and connections between the bobbin guide and parter actuator to cause the parter actuator to operate the parter to part the filling near the shuttle eye as the bobbin leaves the hopper during transfer.

10. In a filling replenishing loom, the combination of a hopper, a transerrer having a bobbin head and bobbin tip engaging mem-

bers, a shaft or stud on which the transferrer is mounted, a bobbin tip guide for directing the tip of the bobbin into the shuttle, a parter for parting the spent filling adjacent the shuttle eye, a bobbin guide mounted for movement by a bobbin as it is transferred from the hopper, a parter actuator pivotally mounted at its inner and outer ends on the transferrer shaft or stud, a connector between said ends 5 extending longitudinally in front of the transferrer stud or shaft in non-interfering relation with parts mounted on said stud or shaft, and connections between the bobbin guide and parter actuator to cause the parter actuator to operate the parter to part the filling near the shuttle eye as the bobbin leaves the hopper during transfer.

11. In a filling replenishing loom, the combination of a hopper, a transferrer shaft, a 20 transferrer mounted on said shaft, a parter for parting the spent filling adjacent the shuttle eye, a bobbin guide mounted for movement by a bobbin as it is transferred from the hopper, a parter actuator including a yoke member 25 mounted for rocking movement on the transferrer shaft at opposite sides of the transferrer, a connection between the ends of the yoke off-set from the transferrer shaft, and connections between the said member and the bobbin guide to cause the parter actuator to operate the parter to part the filling near the shuttle eye as the bobbin leaves the hopper during transfer.

12. In a filling replenishing loom, the combination of a hopper, a transferrer for transferring a bobbin from the hopper to the shuttle, a parter for parting the spent filling along a side wall of the shuttle, mechanism including a yoke member for moving the parting 35 means into operative position on call for replenishment of filling, a bobbin guide mounted for movement by a bobbin as it is transferred to the shuttle, and mechanism for actuating the parter including a rocking yoke 40 member adapted to be actuated by the movement imparted to the bobbin guide by the incoming bobbin to actuate the parter to part the filling along the bobbin.

In testimony whereof, I have signed my 50 name to this specification.

HARRY A. DAVIS.
